(57) **CLAIM**

We claim the ornamental design for pipe flashing, as shown and described.

DESCRIPTION

FIG. 1 is a perspective view of our design for a pipe flashing;

FIG. 2 is a top plan view of the pipe flashing shown in FIG. 1;

FIG. 3 is a side elevation view of the pipe flashing shown in FIG. 1;

FIG. 4 is a bottom plan view of the pipe flashing shown in FIG. 1; and,

FIG. 5 is a section view taken along line 5—5 of the pipe flashing of FIG. 1.
